BINDING DEVICE FOR PANEL-BOARDS.

1,166,149.

Specification of Letters Patent.

Patented Dec. 28, 1915

Application filed November 30, 1914. Serial No. 874,855.

To all whom it may concern:

Be it known that I, RAYMOND H. OLLEY, of Syracuse, in the county of Onondaga and State of New York, have invented a 5 certain new and useful Binding Device for Panel-Boards, of which the following is a specification.

This invention relates to panel boards and has for its object a terminal construction or binding device therefor, which is 10 particularly simple and economical in manufacture and highly efficient and durable in use; and the invention consists in the combinations and constructions hereinafter 15 set forth and claimed.

In describing this invention, reference is had to the accompanying drawings in which like characters designate corresponding parts in all the views.

20 Figure 1 is a side elevation of this terminal or binding device for panel boards, the contiguous portions of the panel board being also shown: Fig. 2 is a vertical sectional view of parts seen in Fig. 1. Figs. 25 3, 4 and 5 are perspective views of the sleeves of insulation forming part of this binding device. Figs. 6 and 7 are modified forms of the intermediate sleeve.

1 designates the base of the panel board, 30 which for convenience is considered as in horizontal position.

2 is one of the conducting bars of the panel board.

The terminal or binding device comprises 35 a post including a support, a plurality of spacing rings 3 arranged one above the other on the support and adapted to receive a connecting member, as 4, between them, a sleeve 5 of insulation inclosing the lowermost spacing ring 3^a, an intermediate sleeve 6 inclosing the intermediate spacing rings, that is, all the spacing rings except the lowermost 3^a and the topmost 3^b, and a third sleeve 7 inclosing the topmost ring 3^b.

45 In this embodiment of my invention, the spacing rings 3 are mounted upon a screw 8 which threads into the upper end of the lowermost spacing ring 3^a; and the support of the post includes said screw 8, a second 50 screw 9 extending through the base of the panel board from the underside thereof, and threading into said lowermost ring 3^a, and a block or sleeve 10 upon which the sleeve 5 and ring 3^a rest, the screw 9 extending axially through the sleeve 10.

Preferably, the conducting bar 2 is deflected from the base 1 and the end 11 thereof is offset from the base and lies in a depression 11^a in the upper end of the block 11, and the lowermost ring 3^a contacts with 60 the end 11 of the bar 2.

Suitable set screws 12, 13, hold the screws 8, 9, from turning relatively to the lowermost spacing ring 3^a and usually the sleeve 5 is provided with a work hole 14 through 65 which the set screw 12 is readily accessible for the purpose of removing the screw 8 and parts mounted thereon.

The sleeve 5 terminates short of the upper end face of the lowermost sleeve 3^a; the top sleeve 7 is formed with a cutout 15 in its lower edge exposing the edge of the lower end face of the topmost spacing ring 3^b; and the intermediate sleeve 6 terminates short of the upper end of the second spacing ring 3 from the top and is formed with a transverse slot or slots 16 arranged to expose the edges of the abutting end faces of the intermediate rings 3 which are inclosed by said sleeve 6. The intermediate 75 sleeve 6 is also formed with a cutout 17 in its lower face arranged to expose the edge of the lower end face of the spacing ring contiguous to the lowermost ring 3^a. Owing to the slots 16 and the cutouts 15 and 80 17, the edges of the abutting end faces of the rings are exposed so that they are accessible to the connecting member 4 which is insertible between any two of the spacing rings. The intermediate sleeve may have 85 one or more slots therein, as shown in Figs. 4, 6 and 7.

The spacing rings 3 are limited in their separating movement to a distance equal to the width or thickness of the connecting 95 member 4, by means of a nut 18 screwing on the upper end of the screw 8 against the uppermost spacing ring 3^b, the nut having an insulating handle or knob 19 fixed thereto, and the outward movement of the 100 nut is limited by a suitable bur or head 20 on the screw 8.

The sleeves 6 and 7 are connected together so that the turning of the top sleeve 7 is transmitted to the sleeve 6, and as here 105 shown, the intermediate sleeve 6 is formed with a mortise 21 at its upper end opposite to the side in which the slots 16 are formed; and the topmost sleeve 7 is formed with a tenon 23 located opposite the cutout 15, the 110

tenon 23 being complementary to the mortise 21 of the intermediate sleeve.

24 is a brace member forming part of the panel board structure, said member having 5 a suitable opening through which the sleeve 7 extends, and the sleeve being provided with a head or flange 25 lapping the upper face of the brace by means of which head the sleeves 6, 7 may be turned to bring the 10 slots 16 and spaces between the sleeves so that they face a set of meter bars on one side of the post, or another set on the opposite side of the post.

This terminal or binding device is particularly applicable for use in metering 15 panel boards having meter bars arranged one above the other, as will be understood by those skilled in the art, and the transverse slots 16 and spaces between the sleeves 20 5, 6, and 6, 7, are aligned with the meter bars.

In operation, the connecting member is engaged with one meter bar and can be inserted through the aligned slot 16, or space between the sleeves 5, 6, or 6, 7, and between 25 two of the spacing rings providing no other connecting member is inserted between two other of the spacing means.

This binding device is particularly advantageous in that it is economical in construction, as it does not require as expensive tools or dies to manufacture the same as the binding devices in which the intermediate sleeves are composed of several parts.

What I claim is:—

35 1. A binding device for panel boards comprising a post, spacing rings encircling the post, one above the other, and insulating means encircling the post and including a sleeve encircling the lowermost ring and 40 terminating short of the upper face thereof, an intermediate sleeve encircling the remaining spacing rings with the exception of the topmost and resting on the upper face of the first sleeve and having a cutout in its 45 lower face whereby the edges of the abutting end faces of the lowermost ring and the next ring above the same are exposed, the intermediate sleeve having a transverse slot exposing the edges of the abutting end faces 50 of opposing rings inclosed thereby, said

intermediate sleeve terminating short of the upper end of the ring second from the top, and a third sleeve mounted on the upper end of the intermediate sleeve and having a cutout opposed to the upper end of the intermediate sleeve whereby the edges of the abutting end faces of the topmost ring and the ring second from the top are exposed, substantially as and for the purpose described.

2. A binding device for panel boards comprising a post, spacing rings encircling the post, one above the other, and insulating means encircling the post and including a sleeve encircling the lowermost ring and 65 terminating short of the upper face thereof, an intermediate sleeve encircling the remaining spacing rings with the exception of the topmost and resting on the upper face of the first sleeve and having a cutout in its 70 lower face whereby the edges of the abutting end faces of the lowermost ring and the next ring above the same are exposed, the intermediate sleeve having a transverse slot exposing the edges of the abutting end faces 75 of opposing rings inclosed thereby, said intermediate sleeve terminating short of the upper end of the ring second from the top, and a third sleeve mounted on the upper end of the intermediate sleeve and having a cut- 80 out opposed to the upper end of the intermediate sleeve whereby the edges of the abutting end faces of the topmost ring and the ring second from the top are exposed, the intermediate sleeve and the third sleeve 85 being rotatable on the rings and being formed with interfitting means whereby turning movement of the third sleeve is transmitted to the intermediate sleeve, substantially as and for the purpose specified. 90

In testimony whereof, I have hereunto signed my name in the presence of two attesting witnesses, at Syracuse, in the county of Onondaga, in the State of New York, this 28th day of November, 1914.

RAYMOND H. OLLEY.
